GOVERNOR MECHANISM

William E. Kemp, Detroit, Mich., assignor to
 Pierce Governor Company, Anderson, Ind., a
 corporation of Indiana

Application December 15, 1932, Serial No. 647,315
 Renewed June 9, 1937

28 Claims. (Cl. 137—153)

My invention relates to improvements in governors for use with internal combustion engines in which the speed control mechanism of the governor is actuated by the vacuum or difference 5 in pressure which exists in the intake manifold, together with its connecting chambers, of an internal combustion engine, at a point above the engine throttle valve, and pressure of the outside atmosphere; and the objects of my improvement are, first, to provide a governor having means for counteracting the unbalanced forces 10 acting upon a governor valve at its closed or nearly closed positions; second, to provide a governor having means for reducing friction by reducing the pressure upon its moving parts; third, to provide a vacuum type governor with by-pass 15 means located upstream from its governing valve; fourth, to provide a vacuum type governor having a vacuum chamber connected with a fuel intake chamber at points above and below a throttle valve member; fifth, to provide a governor having a by-pass automatically closed or opened by the operation of a throttle valve; sixth, to provide a governor having a pivotally secured 20 mounted link member for connecting a vacuum operated diaphragm and an oscillating lever member; seventh, to provide a governor having spring members secured by a resiliently secured adjusting screw; and eighth, to provide a method 25 for counteracting an unbalanced force acting upon a governing valve during its operative movement by increasing vacuum in a governor housing at the time the unbalanced force acts upon the governor valve.

30 My invention is herein disclosed as being applied to and incorporated in the type of governor mechanism disclosed and claimed in the application for U. S. Letters Patent, Serial No. 637,612, filed by me on October 13, 1932.

35 I attain the above mentioned objects by mechanism illustrated in the accompanying drawings, in which,—

Figure 1 is a plan view of the governor assembly with a portion of its cover broken away 40 to disclose its spring and diaphragm mechanism; Fig. 2, a vertical section taken on the line 2—2, Fig. 1; Fig. 3, a side elevation of the governor assembly with a vertical section of the vacuum actuated mechanism on the line 3—3, Fig. 1; Fig. 4, an end elevation of the throttle valve shaft with its lever or damper means for opening and closing a by-pass opening together with its roller member; Fig. 5, a side elevation of the throttle valve and its attached parts as disclosed 45 in Fig. 4; Fig. 6, a plurality of curves plotted in

variables of the vacuum exerted on a diaphragm and the movement of the diaphragm together with a force curve disclosing the results therewith when my by-pass valve means is used; Fig. 7, a longitudinal section through a by-pass passage equipped with an optional type of automatically operated valve therein; Fig. 8, a vertical section of the throttle valve in its housing on the line 8—8, Fig. 1; Fig. 9, an enlarged view of a portion of the diaphragm disclosing different positions of the diaphragm; Fig. 10, a side elevation of a portion of the housing 1, without its cover or housing portion, disclosing the throttle shaft and its damper or valve member together with the vacuum and by-pass passages; and Fig. 11, a vertical section through the damper portion and the by-pass passage, said section being taken on the line 11—11, Fig. 10.

Similar numerals refer to similar parts throughout the several views.

As it is well understood by those skilled in the art, where a throttling type of governor mechanism is employed for maintaining the speed of an internal combustion engine constant under varying conditions of load it is necessary that the 20 throttle valve be statically balanced at all times if perfect control is to result. Particularly in statically balanced butterfly valve types of governor there is an inherent characteristic of the vacuum force in the intake manifold above or on the down stream side of the governor throttle valve to drop off as the valve approaches closed position. Consequently, where a spring of the 25 type having a force curve paralleling that of the vacuum force on the down stream side of the governor throttle valve is employed to oppose closing movement of the throttle valve under the influence of a vacuum acting against the movable wall of the governor, as in the present case, where this drop off is not compensated for, the 30 spring rate continues to increase uniformly as the throttle valve moves into that range of movement within which the vacuum force drops off, and consequently within this range the vacuum force cannot close the throttle valve to the position which is should against the increasing force of the spring in order to hold the speed of the engine constant. The result is that where such 35 drop off in the vacuum force is not compensated for, but the load on the engine is relieved and the 40 throttle moves into the range at which the vacuum force drops off, the engine speeds up beyond that range at which it is intended to be governed.

The ill-effect of this drop off in the vacuum 45

curve as the throttle valve approaches closed throttle position may be compensated for mechanically as in constructions heretofore suggested, but it has been found that this ill-effect 5 may be more easily and more certainly avoided, and with less complications in construction, by varying the force of the vacuum acting upon the movable member controlling the position of the throttle valve so as to cause the vacuum force 10 acting upon such movable member to follow a predetermined and arbitrary force curve rather than the force curve of the vacuum as it actually exists on the down stream side of the governor throttle valve within the intake manifold. In 15 accordance with the present invention the degree of vacuum applied to the movable wall of the governor mechanism to effect operation of the governor throttle valve is varied from that simultaneously existing in the intake manifold on the 20 down stream side of the governor throttle valve. Specifically, such force is reduced by bleeding on to the active face of the movable wall predetermined amounts of gaseous fluid at a higher pressure than that simultaneously existing on the 25 down stream side of the governor throttle valve, so as to cause the vacuum force curve representing the vacuum forces actually applied to the movable wall to generally follow the curve of the vacuum forces simultaneously existing in the intake 30 manifold on the down stream side of the governor throttle valve during movements of the throttle valve other than adjacent closed position. In those ranges of movement of the governor throttle valve at which the above described drop off occurs, the amount of gaseous fluid 35 bled on to the active face of the movable wall is reduced, as compared to wider open throttle positions, so as to cause the vacuum force actually exerted upon the movable wall to more closely approach the vacuum forces actually existing in the intake manifold on the down stream side of the throttle valve under such circumstances, this bleeding of gaseous fluid on to the active face of the movable wall being so controlled during those phases of movement of the 40 governor throttle valve under which the drop off occurs in the intake manifold that the corresponding portions of the force curve of the vacuum forces actually exerted on the active face of the movable wall is caused to continue along a predetermined desired path paralleling that of the opposing spring without a corresponding drop off. By this means it is possible to statically 45 balance the force of the spring tending to open the throttle valve against the vacuum force tending to close it throughout the entire range of movement of the throttle valve and thereby maintain the speed of the engine constant regardless of the load even though the load is completely removed and the governor throttle valve 50 assumes a closed or substantially closed position.

It will be understood that the above described drop off varies in point of occurrence with the particular type and speed of internal combustion engine upon which the governor is employed. In other words, the drop off is more rapid at high speed than at low speed so that where the engine is governed at a relatively high speed the point where the drop off first becomes apparent will be relatively retarded but its rate of drop off will be greater than would be the case where the engine is governed for lower speed operation. The method and apparatus provided by the present invention are effective under all 75

conditions regardless of the governed speed of the engine.

The housing 1 is provided with the flange surfaces 2 and 3 which are suitably mounted between the intake manifold of the internal combustion engine, a section of the intake manifold being indicated at 4, and the carburetor with which the internal combustion engine is equipped, a portion of the carburetor being indicated at 5, Fig. 2. A gasket 6 may be interposed between the flange surface 2 and the intake manifold 4 and the gasket 7 may be interposed between the flange surface 3 and the carburetor 5. The housing 1 is provided with the holes 8 for securing the governor assembly A and the carburetor 5 to the intake manifold 4.

The governor assembly A is secured between the intake manifold 4 and the carburetor 5 in such a manner that the direction of the flow of the combustible mixture of fuel will be through 20 the carburetor 5 and through the housing 1 from the flange surface 3 to the flange surface 2, said mixture passing through the passage or bore 9 of the housing 1 into the passage 10 of the intake manifold 4.

The housing 1 contains the throttling means which may be in the form of the conventional throttle or butterfly valve 11 which may be secured in the slot 12 in the shaft 13 by the screws 14. The throttle shaft 13 is suitably 25 mounted in the bearings 15 and 16 which are of the antifriction type and may be of the roller type as disclosed or of the conventional ball type. The bearing 15 is mounted in the bore 16 of the boss 17, which projects from the body of the housing 1 while the bearing 16 is mounted in the bore 18 in the boss 19 which projects from the body of the housing 1 and is provided with the surface 20 to which is secured the flange 21 of the housing 26 by the screws 22, the gasket 23 being interposed between the surface 20 and the surface of the flange 21. The bore 16 in the boss 17 is closed at its outer end by the disc plug 24.

The shaft 13 projects into the chamber 25 of the housing 26 and the hub 27 of the lever 28 is secured thereon by the pin 29. The shoulder pin 30 is suitably secured in the lever 28 and the roller 31 is rotatably mounted on said shouldered pin 30. The housing 26 is provided with the circular flange 32 which is provided with the surface 33 against which is clamped the outside or peripheral portion of the diaphragm 34 by the annular housing or ring 35, the annular housing 35 being provided with the surface 36 for contacting the diaphragm 34, the annular housing 35 and the diaphragm 34 being secured to the flange 32 of the housing 26 by the screws 37, the heads 38 of the screws 37 being located flush, as by countersinking, with the surface 39 of the 40 annular housing 35.

The central portion 40 of the diaphragm 34 is clamped between the washers 41 and 42 by means of the rivets 43 which are each provided with the shouldered portion 44 which extend into the holes 45 of the members 49 which extend through the springs 46, 47, and 48, which may be normally flat of the plate or leaf type and also of double cantilever construction as disclosed. The members 49 also extend through suitable and similar 50 holes in the spacers 51, 52, and 53 and into the holes 54 of the plate 55.

The washers 41 and 42 are provided with holes which receive the portion 50 of the yoke member 56 which is riveted over to secure the washers 41 75

and 42 and the diaphragm 34 together. The member 56 is provided with a threaded hole engaged by the threaded end 59 of the screw 57 which further extends through suitable holes of the springs 46, 47, and 48, and through similar holes in the spacers 51, 52, and 53 together with a similar hole in the plate 55, the screw 57 securing the springs 46, 47, and 48, the spacers 51, 52, and 53, the plate 55, the washers 41 and 42, and the diaphragm 34 together in the clamped assembly B, said springs being separated from each other by said spacers. The portion 59 of the screw 57 is reduced in diameter below that of its portion extending through said washers, spacers, 15 springs, plate, and nut, said portion 59 being threaded to engage the threaded hole 60 in the yoke member 56.

The yoke member 56 is pivotally connected with the lever 62 by the link member 90 which is secured to the yoke member 56 by the pin 100, the link member 90 being secured to the lever 62 by the pin 63 which extends through and is suitably retained in the fork portions 64 of the lever 62 and in the yoke portions 58 of the member 56. 20

The lever 62 is pivotally mounted on the shaft 65 which is supported within holes extending within the wall portions of the housing 26 and the bosses 66 connected to said wall portions, the boss 67 of the lever 62 extending between the bosses 66.

The lever 62 is further provided with the fork portions 68 which are further provided with the surfaces 69 which are engaged by the roller 31 which is rotatively mounted on the shouldered pin 30. The hole or orifice 70 extends through the boss 19 and constitutes a connecting passage between the chamber 25 of the housing 26 and the bore 9 of the housing 1. 30

The outer ends of the spring 48 normally rest upon antifriction spring seats constructed by rotatively mounting the rollers 71 on the shafts 71 which may be suitably secured by extending through the wall portions of the annular housing 35. The annular housing 35 is provided with the recesses 73 which contain the rollers 71, the ends 45 of the springs 46, 47, and 48, extending into said recesses 73, said recesses 73 being closed at their lower sides by the flange 74 which is constructed with the semi-cylindrical shaped recess 75 which provides operating clearance for the rollers 71.

It is also to be noted that the diaphragm 34 is provided with an exceptional amount of slack or convoluted portion, which is designated at 76, when the governor mechanism is in the position, as disclosed in Fig. 2, said position corresponding to the full open position of the throttle valve 11 as disclosed by the full lines of said valve 11 in Fig. 8.

The large area of the convoluted portion 76 existing at the beginning of the working stroke of the diaphragm 34 together with the extremely short length of its stroke, which may be maintained at approximately a maximum of one eighth of an inch in an installation such as disclosed in the drawings, eliminates all excessive tension in the diaphragm 34 and thus insures that the diaphragm 34 will always be operated with such minimum stresses therein as will enable it to operate over a long period of time without developing trouble; and without offering undue resistance to movement. 70

The inside edge of the surface 36 of the annular housing 35 is provided with the radius 78, the inside edge of the surface 33 of the housing 26, is provided with the radius 79, and the outer edges, 75 of the washers 41 and 42, adjacent the diaphragm

34, are provided with the radii 80 to eliminate any tendency of abrasion or injury to the diaphragm 34 as it is engaged, by said edges, in its operative movement.

The cover or cap 81 is secured in contact with the surface 39 of the annular housing 35 by the screws 82, said cover 81 thus closing the chamber 83 above the diaphragm 34 and sealing the diaphragm 34, the spring assembly B, and the screw 57 against tampering. The heads of the screws 82 may be provided with holes to receive the sealing wire 84 therethrough, as disclosed in Fig. 1, said sealing wire 84 being provided with the seal 85 to insure the prevention of unauthorized tampering with the adjustment of the screw 57. 15

The cover 81 may be provided with one or more radial slots 72 extending from its peripheral edge to a point beyond the inside edge of the surface 39 of the annular housing 35, said slot 72 thus forming an aperture through which atmospheric pressure is admitted to the chamber 83 and permitted to act upon the upper surface of the diaphragm 34, the space below the diaphragm 34 forming a part of the chamber 25 which communicates with the space above the throttle valve 11 through the hole 70 and the by-pass passage 103, the chamber 25 thus being in direct communication with the passage 10 of the intake manifold 4, and with the passage 122 of the carburetor 5 during a portion of the movement of the 30 throttle valve 11.

When my governor mechanism is installed on an engine, and the position of the throttle valve 11 is varied progressively from its wide open position, as disclosed by full lines in Fig. 8, to a nearly closed position, while the speed of the engine is maintained constant by varying the load upon it, it is found that the pressure above the throttle valve 11 decreases as the valve 11 moves toward a fully closed position, said fully closed position being indicated by the dotted lines 86, Fig. 8. However the variation in pressure above the throttle valve 11 is not directly proportional to its movement, or to the movement of the diaphragm 34, which, in my invention, is substantially proportional to the movement of the throttle valve 11. 40

In relation of this existing pressure above the throttle valve 11, measured in terms of vacuum and movement of diaphragm at constant speed is disclosed in the chart, Fig. 6, by the curve 95. 50 This curve of the chart, Fig. 6, is plotted in variables of the vacuum exerted upon the diaphragm 34 in terms of inches of mercury and movement of the diaphragm measured in thousandths of an inch. The abscissae represent the movement of the diaphragm 34 and the ordinates represent the vacuum exerted upon the diaphragm 34. The curve 87, is plotted in terms of pull upon the diaphragm 34 in pounds and movement in thousandths of an inch. The abscissae represent the 60 movement in thousands of an inch and the ordinates represent the pull in pounds. It is to be understood that the term vacuum, as herein used will always be interpreted to mean the difference between the pressure existing above the throttle 65 valve 11 and atmospheric pressure.

Thus it will be understood that, since the space above the diaphragm 34 is subjected to atmospheric pressure, the curve 95 in Fig. 6, discloses the unit pressure acting upon every unit surface 70 of the diaphragm 34, also said curve 95 discloses that the pressure above the throttle 11 is lower than atmospheric pressure at all diaphragm positions i. e. at all engine loads. It therefore follows that at constant speed and decreasing load, 75

the atmospheric pressure tends to move the diaphragm 34 downwardly at all of its positions, and this in turn causes the throttle valve 11 to move toward a closed position. The actual net force 5 resulting from the vacuum pull upon the diaphragm depends upon the size and shape of the diaphragm. I have found that a flat, non-convoluted diaphragm requires a relatively great force to move it away from a mean position of 10 equilibrium and that this force increases as the displacement from position of equilibrium increases, and its magnitude even for a small displacement, such as used in this device, may become larger than the applied vacuum pull. Also 15 the rate at which this force varies with respect to diaphragm movement is not suitable for proper balance of vacuum and other forces, inasmuch as it assists the vacuum force when the valve is at or near a wide open position and opposes the 20 vacuum force when the valve is at or near a closed position, making it unsuitable for use in a governing device. The convoluted diaphragm 34 herein disclosed eliminates the above mentioned difficulty.

25 The force upon the diaphragm 34 varies when it is subjected to a constant non-pulsating vacuum and progressively moved downwardly through its entire range of movement.

Thus the force upon my convoluted diaphragm 30 at constant vacuum, varies uniformly over its entire range of movement and there is no great difference between the force transmitted by the diaphragm, at constant vacuum, as it is displaced through its range of movement. Thus in Fig. 6, 35 the curve 88, shows the actual force transmitted by the diaphragm as a result of being subjected to this variable vacuum as indicated by the curve 95. The curve 88 shows the actual force transmitted by the diaphragm when subjected to a 40 similar constant speed vacuum obtained at a somewhat higher constant engine speed.

If a resistance is provided such that at any 45 diaphragm position the resistance will exactly balance the force acting upon said diaphragm, as obtained from curve 88 of Fig. 6, the governor will tend to maintain a constant engine speed.

It is known that an attempt to obtain isochronous 50 operation invariably results in surging, unless special means, such as dash pots, gag pots, or similar means are provided. In order to insure stable operation in my invention, three 55 stabilizing elements in my construction are thus provided; namely, the novel spring assembly B, an air dash pot, and the by pass valve mechanism hereinafter described.

My governor mechanism results in the development 60 of forces which tend to check any instantaneous tendency toward harmonic speed fluctuation or surging of the governing mechanism, as fully disclosed in the above patent application, No. 637,612.

The governing becomes non-isochronous and a 65 definite difference in the speed of the governed engine is introduced between its full and no load operation, that is, the speed gradually increases as the load upon the engine diminishes.

It will be noted, that the arrangement of the 70 various parts of my device is such that relatively a large size of diaphragm may be used without unduly increasing the height of the governor assembly A. The large area of the diaphragm 34 provides relatively powerful operating forces 75 which make it possible to maintain a small dif-

ference between the full load and no load speed of the governed engine.

Referring again to the drawings it will be noted that the volume of the air contained in the chamber 25 of the housing 26, below the diaphragm 34, 5 is relatively large. Inasmuch as no air can escape from the chamber 25, except through the orifices 10 and 103, it follows that any tendency toward rapid cyclic movements of the diaphragm 34 will be checked and eliminated by the production of 10 resisting pressures in the elastic medium below said diaphragm 34, in other words, the chamber 25 below the diaphragm 34 forms a dashpot. The effect of this dashpot in causing dynamic 15 stability of my governor mechanism may be varied at will by varying the size or length of orifices 10 and 103.

Referring again to Fig. 6, it is to be noted that the curve 88 is substantially straight at its lower 20 end, and that said straight portion is continued as a curve of gradually increasing radius of curvature with no abrupt changes in said radius of curvature of the curve 95. If abrupt changes 25 in radius of curvature were present, such as those present in a curve which would be developed by drawing tangents to the curve 95 at various points, it follows that some portions of this curve, composed of tangents, would have a rate 30 of change of force with respect to deflection equal to or less than at a corresponding portion of the curve 88. Accordingly the governor mechanism would tend to operate isochronously at said positions and hunting or surging would inevitably follow. It is therefore apparent that if a governing 35 mechanism is to provide a close and stable speed control, the balancing resistance curve must have no abrupt changes in curvature.

In order to produce such a desired balancing 40 resistance an assembly B comprising the flat springs 46, 47, and 48, and the spacers 51, 52, 45 and 53 are provided as disclosed. The rate of change of force with respect to deflection of the lowermost spring 48, corresponds exactly to the lower portion of the curve 88 of Fig. 6. After the diaphragm 34 is actuated downwardly by 45 atmospheric pressure through a certain length of movement, the ends of the spring 47 contact with the end portions of the lowermost spring 48 and as the downward movement of the diaphragm progresses, the distance between the point of 50 contact of the spring 47 and the center line of the diaphragm 34 progressively diminishes, thus causing a gradual decrease in the effective length 55 of the spring 47 and a consequent gradual increase in the combined rate of resistance of the spring 47 and the lowermost spring 48. Further downward movement of the diaphragm 34 brings into action the spring 46.

By properly selecting the dimension of said 60 springs and the thickness of said spacers, any 65 curve, of the general character shown by the curve 88 of Fig. 6, may be developed.

The sensitiveness of a governor mechanism in 70 responding to small speed fluctuations depends, among other things, upon the amount of work 75 done by its power element, per stroke, as compared to the negative work which must be done in overcoming friction per stroke. Since it is impossible in a mechanism of this type, to eliminate friction entirely, it is evident that for a given sensitiveness, a definite amount of work must be done by the power element of said governor mechanism. Work being the product of force and distance, it follows that since the arrangement of parts in my invention is such that a 75

large size diaphragm 34 may be used, the operating stroke is relatively short. It also is evident that the deflection of the balancing springs will be short, and consequently, a relatively small adjustment is required to produce a large rate of change in speed at which the governor will control its associated engine. Accordingly, it is possible to adjust my governor mechanism to operate with a great range of engine speed without sacrificing compactness of the governing unit.

The governing mechanism herein disclosed eliminates all operating difficulties caused by abrasives and the leakage of air, as the diaphragm 34 prevents air leakage and is not retarded in its movement by dust or dirt. Because of the novel shape of the diaphragm 34, its rate of resistance to movement is very low. The structure of the balancing springs and the method of their selection provides a smooth continuous balancing resistance, which together with the dashpot action of the chamber 25, insures responsive and accurate governing control and also furnishes a wide range of speed adjustment. Also inasmuch as no retardation or restriction of mixture flow is set up, these desired results are obtained without the loss of engine power.

It is also to be especially noted that the design and assembly of the balancing springs of the spring assembly B is such that no means is provided or is necessary for limiting the balancing resistance of the springs at any time either individually or progressively. Each of the balancing springs of my invention are capable of and are adapted to provide a continuous and uninterrupted progressively increasing resistance to the movement of the diaphragm 34 throughout the total length of its force exerting stroke after each of said balancing springs begins to exert a balancing resistance.

It is also to be noted that the housing 26 is constructed with the recess 91 which provides an entrance into the chamber 25 when the disc plug 92 is removed, said disc plug 92 normally closing the chamber 25. By removing the disc plug 92, knocking out the shaft 65, and by knocking out the pin 100, the lever 62 together with its connected link member 90 may be withdrawn through the opening of the recess 91, thus providing an efficient disassembly of portions of the governing mechanism for service or other requirements without the necessity of the removal of the housing 26 from the housing 1.

The tapped holes 93 in the annular housing 35, as disclosed in Fig. 1, permits the removal of the screws 82 and the cover 81 for inspection or service requirements without disturbing the annular housing 34 or the spring assembly B.

It is also to be noted that the throttle valve 11 is of the statically balanced type, the shaft 13 extending transversely through the vertical center of the bore 9 of the housing 1, said throttle 11 having approximately the same length on each side of the shaft 13.

It is to be especially noted that the peripheral portion 89, of the diaphragm 34, which is clamped between the surfaces 33 and 36 extends in a plane so that the neutral axis of said peripheral portion 89 is indicated by the line 92', in Fig. 9. The central portion 40 which is clamped between the washers 41 and 42 is so located above the line 92 at one end of its movement, that said central portion 40 will be approximately at the position indicated by the dotted lines 93, at the other end of its movement, the convoluted portion 76 having assumed the position indicated by the dotted

lines 94. It is thus to be noted that the effective movement of the central portion 40 is approximately equal on both sides of the line 92, said central portion 40 having a relatively short movement which, due to the convoluted portion 76, sets up a minimum of flexing stresses in the diaphragm 34 and insures that the vacuum forces exerted thereon will be utilized with a very minimum of loss of the effective vacuum forces exerted on the diaphragm 34, also further insuring that the diaphragm 34 will operate over a long period of time without injury. It is also to be noted that the convoluted portion 76 will provide a much more efficient means for transmitting the forces imposed thereon by vacuum, to the governing mechanism connected therewith, than would be the case if the section of the convoluted portion 76 was constructed with a cross section having a lesser depth, it having been found by repeated tests that if said cross section is reduced in depth to have a lesser amount of material in the convoluted portion 76, the effective area of the diaphragm is reduced with consequent greater loss between the vacuum forces developed in the engine and the actual net force developed by the diaphragm 34 due to the imposition thereon of the vacuum forces. Thus it will be seen that the diaphragm 34 actuated by vacuum in my invention represents a distinct advance in operating efficiency over a diaphragm having a normal amount of material connecting a fixed peripheral portion with a central clamped portion. It is to be noted that the overall height of the convoluted portion 76 of my invention is approximately twice the length of the stroke of the diaphragm 34.

The lever 28 attached to the throttle shaft 13 is provided with the lever arm, or damper portion 101 which is adapted to move with the throttle shaft 13 and cover and uncover the bypass passage 103 which connects the vacuum chamber 25 with the passage 9 at a point below or upstream from the throttle valve 11.

Referring now to Fig. 6, it will be noted that the curve 95 represents the degree of vacuum in the intake manifold above the governor throttle valve 11 and that shortly after the throttle valve has begun its closing movement from open throttle position, the curve 95 increases uniformly and along a substantially straight line until it reaches a position corresponding with substantially closed throttle position where it drops off rather rapidly, as indicated at 95'. Curve 88 represents the force exerted by springs 46, 47 and 48 in opposing downward movement of the diaphragm 34 and, as previously noted, this force continues along a uniform path without any drop off corresponding to the drop off 95' in the curve 95. As will be apparent, if the force represented by the curve 95 was relied upon to balance the force of the springs represented by the curve 88, as soon as the throttle valve approached nearly closed position, corresponding to the drop off portion 95' of the curve 95, the vacuum force in the intake manifold would be insufficient to balance the force of the springs at such time with the result that the force of the springs would open the throttle valve 11 to a greater extent than that required to maintain the governed speed of the engine, and, consequently, the speed of the engine would increase beyond its intended governed speed until the degree of vacuum in the intake manifold would have increased sufficiently to balance the force of the spring.

In accordance with the present invention, in-

stead of directly relying upon the force of the vacuum within the intake manifold, as represented by the curve 95 and its portion 95' for actuating upon the diaphragm 34 to control the valve 11, as in previously suggested constructions, a vacuum force represented by the curve 87 is applied directly to the diaphragm 34 to control the movements of the valve 11. As will be noted from an inspection of Fig. 6, the upper portion of the curve 87 increases uniformly beyond the corresponding throttle position represented on the curve 95 by the portion 95' at which the drop off occurs. This difference between the curves 95 and 87 is obtained by the use of the by-pass orifice 103 of predetermined dimension for a particular governor installation and located on the up-stream side of the throttle valve 11. This orifice 103 bleeds a predetermined amount of fuel mixture from the intake manifold on the up-stream side of the throttle valve 11 into the diaphragm chamber 25 and thus reduces the degree of vacuum acting upon the diaphragm 34 as communicated thereto from intake manifold on the down-stream side of the throttle valve 11 through the orifice 10 whenever the throttle valve is closed sufficiently to create a pressure differential on opposite sides of the same. This orifice 103 is allowed to remain unrestricted over that range of movement of the throttle valve 11 at which the curve 95 increases uniformly and consequently the curve 87 parallels the corresponding portion of the curve 95. However, when the throttle valve 11 moves toward nearly closed position at which point the curve 95 begins to break off, as at 95', the damper 101 on the lever 28 begins to overlap the orifice 103 and begins to restrict the flow of combustible mixture from the intake manifold on the up-stream side of the throttle valve 11 into the diaphragm chamber 25, and this has the effect of reducing the pressure differential between the diaphragm chamber 25 and the intake manifold on the down-stream side of the throttle valve 11 and preventing a corresponding drop off in the curve 87. As the throttle valve moves still further toward fully closed position, the damper 101 will move further over the orifice 103 to further restrict the flow of combustible mixture through it and, consequently, will act to further reduce the differential between the vacuum force exerted in the diaphragm chamber 25 and the intake manifold on the down-stream side of the throttle valve 11 and thus continue to prevent a corresponding drop off in the curve 87. Thus, it will be apparent that, by properly proportioning the orifice 103 and the damper 101, the degree of force acting in the diaphragm chamber 25, may be and is actually increased uniformly to maintain the static balanced relationship between the force acting on the diaphragm tending to close the throttle valve 11 and the force exerted by the springs 46, 47 and 48 tending to open the throttle valve, regardless of the fact that the vacuum in the intake manifold on the down-stream side of the throttle valve is actually dropping off when the throttle valve is within the particular range of movement described. By this means, it will be understood that the speeding up of the engine beyond intended governed speed when the throttle valve is in closed or nearly closed position, is positively and effectively prevented.

It is to be noted that the damper portion 101 is provided with a surface 105 which is so located 75 by the shoulder 105', relative to the surface 20

of the housing as to provide the clearance space 107 therebetween and by reducing or increasing this space 107 between the surfaces 105 and 20, and by varying the areas of the clearance space 107, various closing effects may be obtained 5 to accomplish variable increased or decreased force effects upon the diaphragm 34 thus varying the portion 104 of the force curve 88 as desired.

It is to be thus noted that I have provided a 10 method of reducing friction with consequent reduced pressures on moving parts, which is one of the most objectionable elements in governing mechanisms, in a vacuum type of governor and have further provided a method for counteracting 15 the unbalanced force acting upon the governing valve at the closed positions of the governing valve.

It may be desired to use other means of accomplishing this new result and I have disclosed 20 one of such optional means in Fig. 7 in which the by-pass passage 106 is provided with the valve seat member 107 which is provided with the passage 123 which connects with the passage 106 and with the smaller passage 108 which connects 25 with the passage 9, the inner end of the passage 108 forming a stop shoulder for contacting with the valve member 109 which is provided with a triangular shaped head 124 which is engaged by the spring 111 which tends to always maintain 30 the head 124 of the valve member 109, in contact with the stop shoulder of the passage 108, and thus maintaining the by-pass passages 123, 106 and 108 in communication with the passage 9, 35 when the tension of the spring 111 being overcome reaches a predetermined value, thus causing the valve member 109 to seat on the valve seat portion of the passage 123 and close or partially close the passage 123 at the closed or nearly 40 closed position of the throttle valve 11. With the throttle valve 11 in a closed or nearly closed position, the diminished vacuum in the passage 9, below or upstream from the throttle valve 11 enables the vacuum in the chamber 25, which is 45 always connected with the passage 9 at a point above or downstream from the throttle valve 11, to easily maintain the valve member 109 in a closed or nearly closed position to accomplish similar results to the damper member 101 when 50 it closes or nearly closes the by-pass orifice 103 to increase the vacuum in the chamber 25 and to thus alter the force curve 88 to effect a continued balance between the force acting on the diaphragm 34 and the resisting force set up by 55 the balancing springs.

It is to be noted that the use of the link member 90 pivotally connected at its respective ends, with the yoke member 56 and the lever 62, will permit the pin 63 to travel in an arc about 60 the center of the shaft 65 while the yoke member 56 and its connected parts travel in a vertical path without causing any bending or torsional action to be developed in the spring and diaphragm assembly.

The screw 57 is provided with the shoulder 113 and is further provided with the knurled head 114 for contacting the resilient arms 115 of the locking member 116 which may be clamped between the plate 55 and the spring 46, the 70 resilient arms 115 permitting the screw 57 to be adjustably moved to vary the position of the diaphragm 34, relative to its connected parts, the resilient arms 115 immediately locking the screw 57 again in its adjusted position.

The heads of the screws 22 may be provided with suitable holes to receive the sealing wire 117, as disclosed in Fig. 1, said sealing wire 84 being provided with the seal 118 to insure the prevention of unauthorized tampering or removal of the housing 26 from the housing 4. The member 119 may be suitably mounted in the wall of the housing 26 in such position as to permit the head 120 thereof to contact the forked portions 64 of the lever 62 and form a stop therefor to limit the movement of the lever 62 and its connected parts beyond predetermined positions.

It is to be understood that the throttle valve 11 used in this disclosure is of the conventional butterfly type, which is statically balanced, that is, it is supported by the throttle shaft 13 through its geometrical center line. I have discovered that a statically balanced throttle valve of the butterfly type, is not balanced dynamically particularly at high speeds as heretofore disclosed. Thus when the governor is installed on an engine, and the engine caused to operate at a constant speed by varying the load upon it, the flow of the mixture by the valve causes it to tend to move toward a closed position when it is at or adjacent a closed position.

In the following claims it will be understood that the term "vacuum force" is meant the force of the vacuum or partial vacuum being exerted at any specified point in the engine or governor, and that the term "vacuum force curve" is the curve which would be obtained by plotting the variations in such vacuum force for different increments of diaphragm or throttle valve movement at constant engine speed and varying engine loads.

The unbalanced torque upon the valve is transferred through the throttle lever 28, lever 62, and link 90 to the diaphragm 34. The effect of this unbalanced torque upon the curve 88 is shown by the dotted portion 102.

I claim:

1. In a governing mechanism for an internal combustion engine having an intake fuel passage, the combination of a housing having a passage connecting with the intake passage of the engine, throttle means in the passage of said housing, a second housing having a relatively large chamber, a pair of passages connecting the passage of said first mentioned housing with the relatively large chamber of said second housing, said pair of passages connecting with the passage of said first mentioned housing at points above and below the axis of said throttle means whereby to permit transfer of gaseous fluid in said fuel passage through said chamber around said throttle means, said pair of passages permitting the relatively large chamber of said second housing to act as an air dash pot to insure stability of the governing mechanism, and a flexible diaphragm suitably mounted to form a portion of the wall of the relatively large chamber of said second housing, said flexible diaphragm being operatively connected with said throttle means to control the movement thereof, and normally being in open communication with both of said passages.

2. In a governing mechanism for an engine provided with an intake passage, the combination of throttle means in the intake passage of the engine, governing means operatively connecting with said throttling means and operated by the vacuum force in said passage on the downstream side of said throttle means, and means for counterbalancing an unbalanced force acting upon said throttle means only at those closed or

nearly closed positions of said throttle means where the vacuum force in said passage tends to drop off.

3. In a governing mechanism for an engine having an intake passage, the combination of a housing having a vacuum chamber, a movable wall in said chamber, said housing being provided with a pair of passages connecting the vacuum chamber with said intake passage, throttle means in said intake passage between the points of connection of said pair of passages therewith and operatively connected to said movable wall, and means for obstructing one of the pair of passages of said housing to retard the relief of the vacuum in the chamber of said housing only when said throttling means approaches that substantially closed position thereof at which the curve of the vacuum forces in said intake passage tends to fall off, said means being operated by the movement of said throttle means.

4. Governing mechanism for controlling the speed of an internal combustion engine having an intake passage, comprising a throttle valve in said passage, a chamber, a movable wall in said chamber, means connecting said throttle valve and said movable wall for inter-related movements, said chamber having an opening therein communicating the force of the vacuum within said passage on the down-stream side of said throttle valve with said movable wall, said chamber having a second opening therein communicating the interior thereof with said passage on the up-stream side of said throttle valve, spring means opposing movement of said wall in response to the force of vacuum within said chamber, said spring having a force curve characteristic of a similar nature to the curve of the vacuum force in said passage on the down-stream side of said throttle valve, and means for overcoming the effect of the drop off in said vacuum force curve on the movement of said throttle valve under the influence of said spring means, comprising automatically actuated means for throttling said second opening.

5. A governing means for an internal combustion engine having an intake passage comprising, in combination, a butterfly throttle valve for said passage, a housing having a chamber therein, a movable wall in said chamber, means connecting said movable wall and said throttle valve for inter-related movement with respect thereto, said housing having an opening therein communicating said chamber with said intake passage on the down-stream side of said throttle valve, spring means constantly opposing movement of said movable wall under the influence of vacuum existing in said chamber, said housing having a second opening therein communicating said chamber with said intake passage on the up-stream side of said throttle valve whereby to normally reduce the degree of vacuum simultaneously existing in said intake passage on the down-stream side of said throttle valve from acting to its full extent on said movable wall, and means for decreasing the differential of pressure simultaneously existing between said chamber and said intake passage on the down-stream side of said throttle valve during those phases of operation at which the force curve of the vacuum existing in said intake passage on the downstream side of said throttle valve drops off due to said throttle valve closely approaching fully closed position comprising automatically operatable means for throttling the second mentioned opening.

6. In a governor mechanism for an internal

combustion engine having an intake passage and including a butterfly throttle valve in said passage, a housing having a chamber therein, a movable wall in the chamber operatively connected with the throttle valve for inter-related movement therewith, spring means constantly urging said movable wall toward open throttle position and said housing having an opening therein connecting said chamber with said intake passage on the down-stream side of said throttle valve, the combination of means for overcoming the unbalance of which would otherwise occur at approximately closed throttle position due to the drop off in the curve of the vacuum forces in said intake passage on the down-stream side of said throttle valve, comprising, said housing having a second opening therein communicating said chamber with said intake manifold on the up-stream side of said throttle valve whereby during normal engine operation a pressure differential will be created between said chamber and said intake passage on the down-stream side of said throttle valve, and means movable with said throttle valve for restricting said second opening only as said throttle valve approaches the position thereof at which said drop off occurs whereby to reduce said pressure differential and to prevent a corresponding drop off in the curve of the vacuum forces in said chamber acting on said movable wall.

7. In a governor mechanism for an internal combustion engine having an intake passage and a throttle valve therein, in combination, a chamber, a movable wall in said chamber connected to said throttle valve for inter-related movement therewith, spring means constantly urging said wall toward a position to open said passage by said valve, means providing constant communication between said passage on the downstream side of said valve and said chamber, and means for increasing the effect of said communication on said wall only at those closed or nearly closed positions of said valve at which the vacuum in said passage on the down-stream side of said valve falls off, whereby to offset the effect of said falling off on said mechanism.

8. In a governor mechanism for an internal combustion engine having an intake passage and a throttle valve therein, in combination, a chamber a movable wall in said chamber connected to said throttle valve for inter-related movement therewith, spring means constantly urging said wall toward a position to close said passage by said valve, means providing constant communication between said passage on the downstream side of said valve and said chamber, and means including a second communication between said chamber and the upstream side of said valve and an automatically operable valve controlling the same for increasing the effect of said communication on said wall only at those closed or nearly closed positions of said valve at which the vacuum in said passage on the downstream side of said valve falls off, whereby to offset the effect of said falling off on said mechanism.

9. Governing mechanism for controlling the speed of an internal combustion engine having an intake passage, comprising a throttle valve in said passage, a chamber, a movable wall in said chamber, means connecting said throttle valve and said movable wall for inter-related movements, said chamber having an opening therein communicating the force of the vacuum within said passage on the downstream side of said throttle valve with said movable wall, said cham-

ber having a second opening therein communicating the interior thereof with said passage on the upstream side of said throttle valve, spring means opposing movement of said wall in response to the force of vacuum within said chamber, said spring having a force curve characteristic of a similar nature to the curve of the vacuum force in said passage on the downstream side of said throttle valve, and means for overcoming the effect of the drop off in said vacuum force curve on the movement of said throttle valve under the influence of said spring means comprising a valve in said second opening operable under the influence of pressure differences on opposite sides thereof and spring means constantly urging the last mentioned valve toward a position to close said second opening.

10. Governing mechanism for controlling the speed of an internal combustion engine having an intake passage, comprising a throttle valve in said passage, a chamber, a movable wall in said chamber, means connecting said throttle valve and said movable wall for inter-related movements, said chamber having an opening therein communicating the force of the vacuum within said passage on the downstream side of said throttle valve with said movable wall, said chamber having a second opening therein communicating the interior thereof with said passage on the upstream side of said throttle valve, spring means opposing movement of said wall in response to the force of vacuum within said chamber, said spring having a force curve characteristic of a similar nature to the curve of the vacuum force in said passage on the downstream side of said throttle valve, and means for overcoming the effect of the drop off in said vacuum force curve on the movement of said throttle valve under the influence of said spring means comprising a valve in said second opening operable under the influence of pressure differences on opposite sides thereof and spring means maintained under compression between the last mentioned valve and abutment means constantly urging said last mentioned valve toward closed position.

11. In a governing mechanism for an internal combustion engine having an intake passage, a valve for controlling the flow of combustible mixture through said passage, a chamber, movable means in said chamber connected to said valve for controlling operation thereof, said movable means being in open communication within said chamber with said passage on the downstream side of said valve, means for communicating said movable means with a source of varying pressure whereby to permit a transfer of fluid through said chamber around said valve for varying the last mentioned means whereby the vacuum forces produced on said movable means follows a straight line force curve for various positions of said movable means, and means opposing movement of said movable means by said vacuum forces.

12. In combination with an internal combustion engine having an intake passage, governing means for said engine, comprising a governor throttle valve in said passage, a casing having a chamber therein, a movable wall in said chamber connected to said valve for simultaneous movement therewith, means for opposing movement of said wall in one direction at a substantially constantly varying rate, one side or wall within said chamber communicating with said passage

on the downstream side of said valve and the opposite side of said wall being exposed to atmospheric pressure, whereby to produce a pressure differential on said wall during operation of 5 said engine, and means for varying the pressure acting on said wall in opposition to the first mentioned means by bypassing a controlled amount of fuel mixture around said throttle valve and through said chamber whereby to balance 10 the force of said first mentioned means over at least a portion of the operative range of movement thereof and to effect movement of said wall in proportion to the load on said engine.

13. Governor mechanism for an internal combustion engine comprising, in combination with 15 an intake manifold for said engine and a throttle valve therein, a movable wall operatively and mechanically connected to said valve for correlated movement therewith, spring means opposing 20 movement of said wall in one direction, a chamber enclosing one side of said wall, said manifold having an opening therein on the downstream side of said throttle valve communicating with said chamber and an opening therein on the upstream side of said throttle valve communicating with said chamber, and rotatable means 25 movably connected with said wall for controlling the effective area of the last mentioned opening in accordance with the rotatable position thereof.

14. Governor mechanism for an internal combustion engine comprising, in combination with 30 an intake manifold for said engine and a throttle valve therein, a rotatable shaft for said throttle valve, a chamber, a movable wall in said chamber, means connecting said wall with said valve for 35 interrelated movement, spring means constantly urging said wall toward a position to open said valve, the interior of said chamber being connected to the interior of said manifold, upstream 40 and downstream of said valve by a plurality of passages whereby to subject said wall to a suction effect tending to move it in opposition to said spring means, and a damper mounted on said shaft operable with at least one of said 45 passages to vary the flow therethrough.

15. Governor mechanism for an internal combustion engine comprising, in combination with 50 an intake manifold for said engine and a throttle valve therein, a movable wall operatively connected to said valve for correlated movement therewith, spring means opposing movement of 55 said wall in one direction, a chamber enclosing one side of said wall, means communicating said chamber with the interior of said manifold on the downstream side of said throttle valve, other means communicating said chamber with a source 60 of gaseous fluid of varying pressure of a higher value than that normally existing on said downstream side of said throttle valve, said means being in open communication with each other with said chamber during at least a part of the movement of said throttle valve between its opposite limits, and means variably controlling the effective area of said other means.

16. In a governing mechanism for an internal combustion engine provided with an intake passage, the combination of a vacuum chamber provided with a plurality of bypass openings connecting said vacuum chamber with the intake 70 passage, a movably mounted lever provided with a flange portion adapted to close or open simultaneously one of said bypass openings to control the vacuum in said vacuum chamber, a wall in said chamber moved under the influence of vacuum therein, and a throttle valve controlling 75

the engine passage and connected to said wall, said throttle valve moving toward a full closed position during the closing or opening of said bypass opening.

17. In a governing mechanism for an internal 5 combustion engine provided with an intake passage, the combination of a throttle valve movably mounted in said intake passage, a vacuum chamber provided with a plurality of passages connecting with said intake passage, means for 10 closing or partially opening one of said connecting passages in accordance with the movement of the throttle valve in one direction to vary the vacuum in said vacuum chamber during 15 partial opening movement of said throttle valve, said means being operatively and mechanically connected with said throttle valve, a movable wall in said vacuum chamber movable by the variation in the vacuum therein, and means connecting said wall and throttle valve for interrelated movement.

18. In a governing mechanism, the combination of a housing having an intake passage, a throttle valve movably mounted in the intake passage of said housing, a housing provided with 25 a vacuum chamber, said vacuum chamber being connected with the intake passage of said first mentioned housing by a passage located downstream from the throttle valve, said vacuum chamber being connected with the intake passage 30 of said first mentioned housing by another passage located upstream from the throttle valve, said last mentioned passage controlling the vacuum in the vacuum chamber to produce a straight 35 force curve, a movable member in said vacuum chamber having one face exposed to and actuated by the vacuum in said chamber, the opposite face of said member being exposed to atmospheric pressure, means mechanically interconnecting said movable member and said throttle valve for 40 interrelated movement, and means for balancing the vacuum forces of said member.

19. In a governing mechanism for an engine provided with an intake passage, the combination of a vacuum chamber, means movably operated by the vacuum, throttle means in the intake passage of the engine connected with said movable means for interrelated movement therewith, and means for connecting said vacuum chamber with the intake passage of the engine at 50 a point downstream and at a point upstream from said throttle means to develop during the opening movement of the throttle means varying vacuum pressures on said means movably operated by said vacuum by one portion of said 55 connecting means being in open position in advance of another portion thereof during movement of the throttle means in one direction.

20. A spring and diaphragm assembly for a vacuum operable governor including diaphragm 60 means, a power transmitting member extending therethrough, a plurality of flat leaf springs adjacent the diaphragm means opposite the power applying end of said member, spacing plates between leaf springs, said member having an adjustable connection with the springs for adjusting the position of said springs relative to the diaphragm means, tubular bolts for securing said springs and spacing plates together in rigid relation, and guides, one for each bolt, 70 carried by the diaphragm means and telescopically seated in said bolts, said springs being superposed and aligned relative to each other.

21. A device as defined by claim 20, characterized by the diaphragm means including a pair 75

of reenforcing plates with the diaphragm, therebetween and through which the member extends, and means connecting the plates and diaphragm together and supporting the guides.

5 22. A device as defined by claim 20, characterized by the diaphragm means including a pair of reenforcing plates with the diaphragm therebetween and through which the member extends, and means connecting the plates and diaphragm together, said guides constituting integral extensions of said last mentioned connecting means.

10 23. In a vacuum governor, the combination of a central reenforced diaphragm, a plurality of leaf springs, spacers therebetween, a plurality of rigid connections solely between the springs and spacers, guide means carried by the diaphragm reinforcements and extending toward the springs, other guide means associated with the latter, said guide means having telescopic connection therebetween said springs being superposed and aligned relative to each other.

15 24. A device as defined by claim 23, characterized by each guide means being of multiple character and the connections and one of the guide means being integral.

20 25. In a vacuum operable governor, a combination with a chamber subject to vacuum of the intake of an internal combustion engine, said chamber having a port providing restricted communication with the intake, an intake control valve, the communications with the intake being upon opposite sides of the valve, a diaphragm responsive to the vacuum in the chamber, spring means having a parabolic-like, force-displacement curve associated with the diaphragm and opposing diaphragm movement due to the vacuum, and means rigidly connecting the diaphragm

and spring together, of a control member rigid with the shaft and in the housing and arranged to close and open the port depending on valve positioning, an arm in the housing carried by the shaft for movement thereof, means at one end connected at one end to the arm and at the opposite end to the rigid connecting means for translating axial diaphragm movement into rotary valve movement.

5 26. A device as defined by claim 25, characterized by the addition of a cover means forming with said diaphragm a spring chamber in which the spring means is positioned, a seal means locking said cover means in position, breakage thereof indicating unauthorized access to said spring means.

10 27. A device as defined by claim 25, characterized by the addition of stop means for the means connecting the rigid connection and the arm to prevent movement of the arm in a direction opposite that for which the same is normally intended to move when subjected to increasing vacuum force.

15 28. A device as defined by claim 25, characterized by the addition of a cover means forming with said diaphragm a spring chamber in which the spring means is positioned, a seal means locking said cover means in position, breakage thereof indicating unauthorized access to said spring means, and the addition of stop means for the means connecting the rigid connection and the arm to prevent movement of the arm in a direction opposite that for which the same is normally intended to move when subjected to increasing vacuum force.
